UNITED STATES PATENT OFFICE

EDWIN H. WHITE, OF WORCESTER, MASSACHUSETTS

DESIGN FOR A PLAYING CARD

Application filed November 25, 1932. Serial No. 46,149. Term of patent 7 years.

To all whom it may concern:

Be it known that I, EDWIN H. WHITE, a citizen of the United States, residing at Worcester, in the county of Worcester and State of Massachusetts, have invented a new, original, and ornamental Design for a Playing Card, of which the following is a specification, reference being had to the accompanying drawing, forming part thereof.

The figure is a back view of a playing card, the face of the card being conventional showing my new design.

I claim:

The ornamental design for a playing card as shown and described.

EDWIN H. WHITE.
